UNITED STATES PATENT OFFICE

100,199

DESIGN FOR A DRY CELL BATTERY

Charles F. Burgess, Bokeelia, Fla., assignor to
Burgess Battery Company, Madison, Wis., a
corporation of Wisconsin

Application December 14, 1935, Serial No. 60,080

Term of patent 14 years

To all whom it may concern:

Be it known that I, Charles F. Burgess, a citizen of the United States, residing at Bokeelia, in the county of Lee and State of Florida, have invented a new, original, and ornamental Design for a Dry Cell Battery, of which the following is a specification, reference being had to the accompanying drawing, forming part thereof.

Figure 1 is a front view, Figure 2 is a side view, and Figure 3 is a view in perspective of a dry cell battery, showing my new design.

Characteristic features of the design reside generally in the proportions of the battery whereby the thickness thereof approaches the length of the side faces, and the opening extending through the battery and positioned at the center thereof.

I claim:

The ornamental design for a dry cell battery, substantially as shown and described.

CHARLES F. BURGESS.
